Attorney.

UNITED STATES PATENT OFFICE

LEONARD J. BROWN, OF TACOMA, WASHINGTON

TINT LAYING MACHINE

Application filed May 20, 1929. Serial No. 364,597.

My invention pertains to tint laying machines known as the Ben Day tint laying machines, commonly used for laying tints on metal or paper for the photoengraver and on metal or stone for the lithographer and for other uses where a dot line or other stipple is used.

The object of my invention is to simplify the construction and operation of tint laying machines and to attain more ease and greater accuracy in its use.

Heretofore the tint laying film has been adjusted and controlled by micrometers applied in line with the adjustment, a process in which there is more or less lost motion and inaccuracy. In my improvement the tint laying film is adjusted and controlled by inclined planes and similar mechanical movements actuated by a single micrometer with perfect ease and accuracy.

The attainment of these objects will be shown and described by referring to the accompanying drawings, in which—

Fig. 1 is a top view of my improved tint laying machine inclosed within a fixed frame or case, the top inclosing plate being removed to expose the improved operative mechanism; Fig. 2 is a vertical cross section on line 2—2 looking to the right; Fig. 3 is a front view of Fig. 1, the top plate being in place as it is shown also in Fig. 2; Fig. 4 is a top view of a like machine designed to be operated on pivotally operated levers; and Fig. 5 is a like machine designed to be operated by spiral gears and cams. Similar parts are indicated and referred to by similar characters in each of the several views.

Referring to the drawings, it will be seen that the single micrometer 1 with a compression spiral spring 2 around its shaft will operate and control the inclined contact planes 3—3 formed on the ends of the bar 4 which is designed to slide to the right and to the left. The forward and backward movement is attained by means of the bar 5 formed with inclined contact planes to fit and bear against the inclined planes 3—3 of bar 4. It will be seen that the compression spring 6—6 supported on the side wall of the frame or case 7, will hold the inclined planes

3—3 in positive and constant contact, and these inclined surfaces will react on the bar 5, pressing it toward the left so that its end will bear on and be guided by the finished interior surface of the wall 5" of the frame 55 7 and also on the rear bar 4, pressing it against the interior wall 4" of the frame 7 and toward the right against the action of the spring 2 as controlled by the micrometer 1. The sliding movement of the bar 4 to the right or to the left, attained by turning the micrometer 1, will cause a perfectly parallel movement of the bar 5 forward or backward as desired and, though small, the movement will be made with the utmost accuracy and 60 perfect ease by the use of the single micrometer 1.

The function of the spring 2, compressed between the frame 7 and the bar 4 and encircling the micrometer shaft, is used to 70 eliminate any backlash between the threads of the micrometer screw and the threads in the bar 4 by causing the said threads to always bear on the same side. This spring 2 is always in compression and the micrometer 75 screw shaft is thereby constantly held in tension and there can therefore, be no lost motion in the mechanism. It will also be observed that the complementary inclined surfaces 3—3 and 4—4' on the bars 4 and 5 are each 80 single contact surfaces which are kept in constant contact by the compression springs 6—6. Heretofore a single motion has been attained by forming a slot in one member and a lug in the other riding in the slot, thus 85 producing a double contact between the parts. A very slight wear in either the slot or in the lug will cause the device to act imperfectly, because it will permit a slight unintended motion between the two parts. 90 This defect has been completely eliminated by my improved machine which has the single acting contact surfaces as shown and the springs 6—6 to keep them in contact. The springs 6—6 also keep the bar 4 tightly 95 pressed against the rear inner surface of the frame 7.

The bars 4 and 5 are neatly milled to fit and operate within the inclosing frame 7 which is likewise milled to receive them. 100

The bar 4 is made with small side extension lugs 4'-4' to make sliding contact with the bottom and top of the inclosing frame 7 and is thus kept in exact alinement. Likewise the bar 5 has on its sides milled guide barlike extensions 5' for the same purpose. The inclosing top 12 is shown in Figs. 2 and 3.

Attached to the bar 5 is the usual film holding frame 8-8 in the outer ends of which are inserted the pivotal film holding pointed pins 9-9. These holding pins are actuated by spiral encircling springs as shown in Fig. 3, and one is equipped with a micrometer 10 whereby the film can be finely adjusted to the right or left. The film holding frame and pivotal pins as shown, are common to all tint laying machines and are not new nor novel. However, it is mounted within my improved tint laying machine and is used in combination therewith and will thereby be made to function accurately.

It will now be seen that when the film for laying on tints is mounted on the pivotal pins 9-9, it will be moved forward or backward with ease and accuracy, free of lost motion or vibration. The bar 4 operated and controlled by the single micrometer 1 will, by means of the inclined contact planes at 3, move the spring stabilized bar 5 forward or backward with the utmost nicety, and with it the film carrying frame 8-8 fixed thereto. It is to be observed the bearings on the bar 4 can be made with means for eliminating friction common to bearings of this form.

There are other adjustable means whereby the improved tint laying machine may be operated and controlled by a single micrometer, two of which are shown in Figs. 4 and 5. In Fig. 4, the inclined planes 3-3 above described, by two similar parallel levers 13-13, pivoted to the base of the frame 7 and which are equally operated by the movement of the bar 4 and which engage and operate the bar 5. In Fig. 5 the bar 4 has been substituted by the worm gear rod 19 meshing with two worm wheels 20-20 mounted on the base of the frame 7 to turn therein and each having similar parallel cams 14-14 secured thereto and engaging the bar 5 to operate it.

As to being set level or adjusted as to height, the usual form of foot screws 11, 11, 11, are used.

Having described my invention, I claim—

1. In a tint laying machine, the combination of a frame, a screen carrier mounted therein and adapted to be moved inward and outward therein, a single micrometer mounted in said frame, complementary inclined single acting planes interposed between said micrometer and said screen carrier, and springs holding said inclined planes in continuous contact, whereby the adjustment of said micrometer causes said carrier to move.

2. In a tint laying machine, the combina-

tion of a frame, a screen carrier mounted therein, and adapted to be moved inward and outward therein, a single micrometer mounted in said frame, two pairs of complementary parallel inclined single acting planes interposed between said micrometer and said screen carrier, each pair of said planes engaging on one surface only, and springs holding said pairs of inclined planes in continuous contact, whereby the adjustment of said micrometer causes both ends of said screen carrier to move simultaneously and equally.

3. In a tint laying machine, the combination of a frame, a screen carrier mounted therein, and adapted to move inward and outward therein, springs interposed between said frame and said screen carrier and adapted to cause said screen carrier to move inward in said frame, a single micrometer mounted in said frame, and means actuated by said micrometer and acting in opposition to said springs whereby said screen carrier may be moved outward from said frame.

4. In a tint laying machine, the combination of a frame, a screen carrier mounted and guided therein to move inward and outward therein, springs interposed between said frame and said carrier and adapted to cause said carrier to move inward in said frame, a single micrometer mounted in said frame, and two sets of means, each simultaneously, correspondingly, and equally actuated by said micrometer in opposition to said springs and engaging the ends of said carrier, whereby both ends of said screen carrier are equally moved.

LEONARD J. BROWN.
